the Alien Property CustodianApplication April 2, 1941, Serial No. 386,560
In France October 12, 1939

9 Claims. (Cl. 252—359)

This invention relates to smoke producing means especially adapted to produce artificial clouds of smoke, the primary object of the invention being to provide improvements in such means whereby continuous production of smoke is assured during the time desired by the operator.

Another object of the invention is to improve devices of this character so as to enable them to produce smoke having predetermined coloration which can be varied by the operator at will during the operation of the devices.

These and other objects of the invention are attained through features of construction and relation of parts apparent from the following description and the appended drawings, wherein embodiments of the invention are set for illustration.

In the drawings:

Figure 1 is an axial vertical section through a device according to the invention.

Figure 2 is a front elevation thereof.

Figures 3 and 4 are vertical sections of additional devices according to the present invention.

Figure 5 is a front elevation of an aircraft provided with one of the devices.

Figure 6 is a side elevation of Figure 5.

Figure 7 is a diagrammatic view of a submarine boat provided with one of the devices.

Figure 8 is a detailed view of the device as applied in Figure 7.

Referring in detail to the drawings, the embodiment of the invention shown in Figures 1 and 2 comprises a vessel 1 constituting a magazine closed at its upper part by a removable cover 15 and terminating at its lower part in a master nozzle 16.

The interior 17 of the vessel 1 is divided into upper and lower chambers 17¹ and 17² by a gate or trap door 18 pivotally secured at 19 to the vessel 1, and a return spring 20 operates to raise the trap door toward closed position.

A tube 21 with a removable cover 22 on its upper end is located alongside of the vessel 1 and terminates at its lower end in an auxiliary nozzle 23 which discharges axially within the master nozzle 16.

The operation of this device is as follows:

A first roll 5¹ of combustible material, for example, old moving picture film, is dropped into the vessel 1 after removal of the cover 15, so as to pass the trap door and come to rest on the bottom of the vessel 1, whereafter the roll is set on fire in some convenient manner. The combustion of the roll causes smoke to pass through the

master nozzle 16 and emerge therefrom in a stream f¹.

When the combustion of the roll 5¹ has gone sufficiently far, and a second roll 5² is introduced into the chamber 17¹ of the vessel and falls on the trap 18, the trap swings downwardly along the path f² about its pintle 19, during which action it compresses its spring 20, until the roll 5² falls from the charging chamber 17¹ into the combustion chamber 17², wherein the roll 5² catches fire and thereby produces smoke which escapes through the master nozzle 16.

During the combustion of the second roll 5² a third roll may be introduced into the charging chamber 17¹, and this procedure may be repeated indefinitely, whereby a continuous stream f¹ of smoke from the master nozzle 16 can be obtained. During the operation, the closing of the trap door 18 shuts off the charging chamber 17¹ from the combustion chamber 17², so that backing up of the smoke into the charging chamber 17¹ and into the upper opening of the vessel 1 is prevented.

During the combustion of the rolls 5¹, 5², etc., and the ejection of their white smoke, balls 25 of materials producing various colors may advantageously be introduced into the tube 21 after removing the cover 22, so as to fall into the auxiliary nozzle 23 and produce colored smoke which discharges into the main nozzle 16 and mixes with the other smoke therein so as to color it.

A device according to the present invention offers the following principal advantages:

(a) Continuous production of artificial smoke;
(b) Ease of operation and adaptability to continue the production of either plain or colored smoke as long as the operator deposits in the device the necessary combustible rolls and/or balls at the required time intervals.

Various modifications may be made in the above described devices. For example, as shown in Figure 3, a plurality of vessels 1¹ and 1² mounted side by side may be provided, each being formed in the same manner shown in Figures 1 and 2, and includes covers 15¹ and 15², master nozzles 16¹ and 16², and trap doors 18¹ and 18², and 19¹ and 19².

The rolls 5¹, 5² . . . are successively introduced into the vessels 1¹ and 1², so that the combustions in the vessels are out of phase with each other, the combustion in one vessel being almost finished before the combustion in another vessel begins. In this way uninterrupted production of continuous smoke clouds is obtained.

The tube 21, provided for the reception of the balls 25 of materials producing colored smoke, is

arranged in the middle of the interiors of the vessels 1^1 , and 1^2 , etc. The unit shown in Figure 3 works like the device shown in Figures 1 and 2 and projects a stream f^3 of artificial smoke, in which smoke colored at the desire of the operator has been mixed in the region f^4 .

Figure 4 shows a modification of the device shown in Figure 3, wherein each vessel is self-supporting, and wherein the tubes 21^1 , 21^2 , etc., for the introduction of balls 25 producing colored smoke, are axially disposed. This arrangement enables the production of a smoke stream or smoke cloud made up of component smoke streams of different colorations. It is feasible, for instance, to form a stream composed of three jets, such as blue, white, and red, arranged close together, or any desired variation or shade of these colors, to conform to, for instance, a preferred signal code.

The aircraft mounted device of Figures 5 and 6 comprises the vessel 1 and the master nozzle 16 as in Figures 1 and 2, the said nozzle producing the artificial smoke stream f^1 . The device is so mounted that it can slide as a whole in the body of the aircraft along the path f^6 , so that it is possible to retract the device into the body or to project it from the body when being used for producing smoke.

The submarine mounted device of Figures 7 and 8 is provided with a vessel 1 which receives the roll 5^1 of combustible material in its lower part and which is provided with a side branch 26 having a closing trap 18 which retains the following roll 5^2 , whereby it is possible to obtain a continuous ejection of smoke as already described in connection with the embodiment of Figure 1. The roll 5^1 burns and produces a smoke stream emitted by the nozzle 16 . During this time the roll 5^2 can be introduced into the branch 26 so that it can take the place of the roll 5^1 at the end of the latter's combustion.

The tube 21 for the production of colored smoke terminates at its lower end in an upwardly angulated funnel 27 which receives the balls 25 of materials for producing colored smoke. The master nozzle 16 and the auxiliary nozzle 23 at the upper end of the tube 21 can be closed by a cover. The device is mounted in the hull of the submarine, as shown in Figure 7, so that it can slide vertically as a whole in either direction, whereby it is possible to retract the device into the hull of the submarine when the production of smoke is no longer wanted.

I claim:

1. An apparatus for producing smoke screens, comprising a housing provided with an internal self-closing gate dividing the interior of the housing into an upper smoke producing material magazine and a lower combustion chamber, the gate being arranged to yield downwardly under the weight of a charge of combustible material introduced into said magazine and pass the same into the combustion chamber and then return to closed position, and a discharge nozzle leading from said combustion chamber.

2. An apparatus for producing smoke screens, comprising a housing provided with an internal shiftable gate normally dividing the interior of the housing into a smoke producing material magazine and a combustion chamber, a smoke discharge nozzle communicating with said combustion chamber, an auxiliary housing for receiving other smoke producing material associated with the first named housing and a smoke

discharge nozzle communicating with the auxiliary housing.

3. An apparatus for producing smoke screens, comprising a housing provided with an internal shiftable gate normally dividing the interior of the housing into a smoke producing material magazine and a combustion chamber, a smoke discharge nozzle communicating with said combustion chamber, an auxiliary housing for receiving other smoke producing material associated with the first named housing and a smoke discharge nozzle communicating with the auxiliary housing, said last named discharge nozzle being concealed by the main smoke discharge nozzle.

4. Apparatus for producing smoke screens comprising a housing having a terminal portion thereof formed to provide a smoke discharge nozzle, a swingable gate extending across said housing at a point intermediate the first mentioned terminal portion and another terminal portion of the housing, whereby the interiors of said terminal portions constitute combustion chamber and magazine for reception of a charge of combustible material, respectively, said gate being normally positioned to close the combustion chamber with respect to the magazine and arranged to be displaced by the weight of a charge of combustible material placed in said magazine so as to pass the charge into the combustion chamber, means effecting return of the gate to normal closed position after passage of the charge into the combustion chamber.

5. Apparatus according to claim 4 wherein an auxiliary housing having a combustible material receiving portion and a nozzle is mounted on said housing with the auxiliary nozzle discharging into the first mentioned nozzle.

6. Apparatus according to claim 4 wherein an auxiliary housing having a combustible material receiving portion and a nozzle is mounted on said housing with the auxiliary nozzle discharging into the first mentioned nozzle, said first mentioned discharge nozzle being located at the lower part of the housing and said magazine being located at the upper part of the housing.

7. Apparatus according to claim 4 wherein an auxiliary housing having a combustible material receiving portion and a nozzle is mounted on said housing with the auxiliary nozzle discharging into the first mentioned nozzle, said first mentioned nozzle being located at the upper part of the housing and said magazine being located adjacent to the lower part of the housing.

8. Apparatus according to claim 4 wherein an auxiliary housing having a combustible material receiving portion and a nozzle is mounted on said housing with the auxiliary nozzle discharging into the first mentioned nozzle, said first mentioned discharge nozzle being located at the lower part of the housing and said magazine being located at the upper part of the housing, said discharge nozzle projecting laterally from the housing.

9. Apparatus according to claim 4 wherein an auxiliary housing having a combustible material receiving portion and a nozzle is mounted on said housing with the auxiliary nozzle discharging into the first mentioned nozzle, said first mentioned discharge nozzle being located at the lower part of the housing and said magazine being located at the upper part of the housing, said discharge nozzle projecting upwardly from the upper part of the housing.
